UNITED STATES PATENT OFFICE.

WALTER J. BURCHETT, OF NEW YORK, N. Y.

AUTOMATIC BOTTLE-STOPPER.

SPECIFICATION forming part of Letters Patent No. 764,225, dated July 5, 1904.

Application filed October 9, 1903. Serial No. 176,366. (No model.)

To all whom it may concern:

Be it known that I, WALTER J. BURCHETT, a citizen of the United States, residing at New York, borough of Brooklyn, county of Kings, and State of New York, have made a new and useful Invention in Automatic Bottle-Stoppers, of which the following is a specification.

My invention is directed particularly to automatic bottle-stoppers adapted for use with 10 bottles having mouths or necks of different diameters; and it has for its objects, first, to devise an automatic bottle-stopper which may be easily and cheaply constructed; second, to devise an automatic bottle-stopper the parts 15 of which may be so adjusted as to adapt it for use with bottles having necks which differ materially from each other; third, to devise an automatic bottle-stopper which may be so constructed that when the user grasps the bottle by the neck he will simultaneously withdraw or remove the stopper and maintain it 20 in such removed position so long as he continues to hold the bottle in this manner; fourth, to devise an automatic bottle-stopper which 25 under normal conditions will be yieldingly held with the stopper in a closed position in the mouth of the bottle or which may, if desired, be similarly held in an open position.

For a full and clear understanding of the 30 invention, such as will enable others skilled in the art to construct and use the same, reference is had to the accompanying drawings, and to the following specification, the especial points of novelty being particularly pointed 35 out in the claims at the end of this specification.

Figure 1 is a sectional view taken through the neck and upper portion of a bottle, illustrating also in sectional view the stopper normally held in closed position; and Fig. 2 is a 40 side elevational view thereof illustrating the stopper normally in open position. Fig. 3 is a detail developed plan view of that part of the device which constitutes the support for the operative parts of the stopper and also 45 the means for securing the same detachably to the neck of a bottle.

Referring now to the drawings in detail, in all of which like letters of reference represent like parts wherever used, B represents 50 the neck and upper portion of a glass bottle

of well-known form provided with the usual bead F near the mouth thereof.

D represents the sustaining part of the device, the same being constructed of thin sheet metal, such as steel or case-hardened iron, and 55 stamped in one operation in such manner as to be provided with two or more pairs of arms A A, A A, which when bent into the position shown in Figs. 1 and 2 constitute gripping means for supporting the parts 60 detachably upon the outer portion of the neck of a bottle and near the mouth thereof, the outer ends of the arms being bent outwardly, so that the same may be slipped readily into position with the lower arms below the bead F. 65

T T constitute side lugs, which are turned upward and in an opposite direction to the arms A A, and O O are oblong slots, I I being 70 openings for supporting a rivet R, which when in position pivotally supports the curvilinear operating-handle H.

J is a fulcrum-arm for the cork and its sustaining-cup secured between the lugs T T in the slots O O by a screw S, the adjustment of the fulcrum-arm being when the parts are in 75 position in the direction of the length of the bottle-neck and for the purpose of adapting the use of the parts with bottles in which the bead F is located at different distances from the mouths thereof.

C is a segmental part of a spherical cork or other flexible water-tight material firmly secured by glue or otherwise within a cone-shaped cup C', which in turn is pivotally secured to the upper part of the fulcrum-arm J 85 by a fulcrum-pin K.

E is a lug or ear on one side of the cup C', next to the free end of the short arm of the operating-handle H, said lug or ear being connected to the aforesaid short arm by a metal 90 link L.

M is an operating-spring wound spirally around the rivet R between the lugs T and with its short arm bearing against the outer face of the body part D, the long arm of said 95 spring pressing outwardly against the inner curvilinear surface of the operating-handle H, the arrangement being such that when the parts are in the position shown in Fig. 1 the segmental stopper or cork C is firmly held in 100

closed position. The arrangement of the adjustable fulcrum-arm J, lug E, free end of the operating-handle H, and link L is such that when the user grasps the bottle by the neck 5 B and handle H he thereby causes the cup C', and hence the cork or stopper C, to be removed from the mouth of the bottle and to thus remain until the desired amount of the contents has been withdrawn. This arrangement of these several parts is also such that if it is desired to leave the mouth of the bottle wholly open during the time that it is being filled and without manipulating the operating-handle H the user may turn the cup C' 10 to its extreme open position, such that the action of the spring M, handle H, and link L causes the cup C' to remain in the position shown in Fig. 2 or continuously open. When it is required to adapt the device for bottles 15 having necks of different sizes, it is only necessary to remove the screw S, adjust the fulcrum-arm J to the proper height, and then restore the screw to its normal position. This may be ascertained after a proper trial of the 20 adjustment, the exterior curvature of the segmental cork being such as to adapt it for the mouths of bottles having different internal diameters, as will be readily appreciable on inspection of the drawings.

30 I do not limit my invention to the especial details of construction illustrated in the accompanying drawings.

I believe it is broadly new with me to devise an automatic bottle-stopper having means 35 for automatically causing the same to be held normally in a closed position, and so constructed as to adapt it to be held normally in an open position when it is desired to fill the bottle or maintain the cork or stopper permanently in such open or detached position, and 40 my claims are generic as to these features.

Having thus described my invention, what I claim, and desire to secure by Letters Patent of the United States, is—

45 1. An automatic bottle-stopper consisting of gripping means for securing the same to the neck of a bottle; means for supporting the

stopper adjustably with relation to the first-named means; in combination with an operating-handle yieldingly connected to the stopper and adapted to normally maintain it in a 50 closed position.

2. An automatic bottle-stopper consisting of means for securing the same to the neck of a bottle; adjustable means connecting the 55 stopper with the aforesaid means and an operating - handle pivotally supported by the first-named means and operatively connected to the stopper; together with yielding means between the support and the operating-handle 60 for maintaining the stopper in either an open or a closed position.

3. An automatic bottle-stopper consisting of a segment of a sphere, preferably of yielding material such as cork, a fulcrum-arm to 65 which the same is pivotally secured; a detachable support to which the fulcrum-arm is adjustably attached, said support being provided with means for gripping or grasping the neck of a bottle; in combination with an operating- 70 handle pivotally secured to the support and provided with yielding means for maintaining the stopper in a closed position with relation to bottles having necks of different diameter.

4. An automatic bottle-stopper consisting 75 of a body part provided with yielding arms of which is pivotally secured a cork of substantially spherical contour on one side, said cork being yieldingly connected by a link to an operating-handle which in turn is supported by the body part and is provided with 80 yielding means as a spring for maintaining 85 the cork in closed position.

In testimony whereof I have signed my name to this specification in the presence of two subscribing witnesses.

WALTER J. BURCHETT.
